Patented June 2, 1914.

Fig. 1.

UNITED STATES PATENT OFFICE.

JOHN KAYETAN, OF NEW YORK, N. Y., ASSIGNOR TO KAYETAN-RUES COMPANY, INC.,
A CORPORATION OF NEW YORK.

HONING-MACHINE.

1,098,504.

Specification of Letters Patent.

Patented June 2, 1914.

Application filed January 9, 1913. Serial No. 740,907.

To all whom it may concern:

Be it known that I, JOHN KAYETAN, a citizen of the United States of America, residing at New York, in the county of New York and State of New York, have invented certain new and useful Improvements in Honing-Machines, of which the following is a specification.

The present invention relates to honing machines for razors or the like having concaved surfaces and has for its object to provide means for holding the razor with its concaved surface against the honing stone so that the honing or sharpening thereof can be effectively and rapidly accomplished.

To make my invention more clear the same is illustrated in the accompanying drawing in which similar reference letters denote corresponding parts and in which—

20 Figure 1 is a vertical section through the machine, Fig. 2 is a top plan view and Fig. 3 is a detail.

In the drawings *a* denotes the base plate on which is secured a post *b* and the bearings *c* in which the spindle *d* is borne to which is fixed the hone stone *e*. The hone-stone may be driven by hand from a hand wheel *f* through the medium of a belt *g* or in any other suitable manner. Secured to the 30 bearings *c* and extending longitudinally over the circumference of the hone-stone is a bent wire *h* or the like which serves as a rest for the back of the razor *r*, knife or the like when placed on the hone-stone.

35 Secured to a vertical rod *i* is a fork shaped bracket *j* in which a rod *k* is rotatively borne. Eccentrically mounted on this rod are two lateral clamping cylinders *k* which are connected by a rod *l* mounted in said 40 clamping cylinders. Projecting forwardly from the rod *i* is a horizontal arm *m* which is formed with a tubular downwardly extending projection or sleeve *m'* in which is movably mounted a rod *n*, the lower end of 45 which is formed to a head *n'* connected to the intermediate portion of the rod *l* and the upper end of which is screw threaded and bears a nut *o*. A spring *n''* pressing against the head *n'* is adapted to press the 50 clamping cylinders *k* against the razor *r* or the like. By working the nut *o* up or down the tension of the spring *n''* can be regulated.

The vertical rod *i* is movably supported 55 in a sleeve *p* and is actuated by a spring *p'* which constantly presses it downwardly. Projecting laterally from said rod through a vertical recess *p''* in the sleeve is a pin *i'* with which co-operates a cam shaped arm *p''* pivoted to the sleeve *p*. By swinging this arm *p''* from its normal vertical position, its cam portion engages said pin *i'* and lifts the rod *i* and consequently the rollers *k*.

To allow of razors or the like of various 65 thicknesses being honed on this machine, the sleeve *p*, too, is adjustable in vertical direction. To this end this sleeve is adjustably mounted in a tubular part *q* of a hollow horizontal arm *q'* and is provided on its upper end *q''* with a screw thread on which works a nut *q'''*. By means of a set screw *q''''* the sleeve *p* is held in its adjusted position.

The arm *q'* is adjustably mounted in an 70 elbow shaped tube *s* and can be adjusted in longitudinal direction by means of a headed screw *t* working in the threaded hollow *q''''* of the arm *q'*. This horizontal adjustment of the arm serves the purpose to allow of the rollers *k* being brought nearer to or farther 75 from the rest *h*, according as the width of the razor or the like requires. The elbow tube *s* is adjustably mounted on the post *b* of the machine.

The lower part of the hone-stone is 80 enclosed by a horizontally movable case *u* which in front has fixed to it a stone *v* serving to remove a superfluous quantity of lubricant from the hone-stone during rotation of the latter and to constantly even up the 85 hone-stone.

What I claim and desire to secure by Letters Patent is:

1. In a honing machine for razors having concaved surfaces, the combination with a 90 revoluble hone stone, of a vertically adjustable eccentrically supported clamping cylinder and means for pressing said clamping cylinder toward said stone so as to clamp the razor between said clamping cylinder 95 and the honing stone.

2. In a honing machine for razors having concaved surfaces, the combination with a 100 revoluble hone stone, means extending longitudinally over the said stone and serving as a rest for the back of the razor, a vertically adjustable eccentrically supported 105

clamping cylinder and means for pressing said clamping cylinder toward said stone, so as to clamp the razor between the clamping cylinder and the honing stone.

5. 3. In a honing machine for razors having concaved surfaces, the combination with a revoluble honing stone, a vertically adjustable bracket, a clamping cylinder eccentrically supported from said bracket and means 10 for pressing said clamping cylinder toward the honing stone so as to clamp the razor between said clamping cylinder and the said stone.

15. 4. In a honing machine for razors having concaved surfaces, the combination with a revoluble honing stone, a vertically and horizontally adjustable and eccentrically supported clamping cylinder adapted to engage

the razor between itself and the honing stone and means for pressing said clamping cylinder so as to clamp the razor in position. 20

5. In a honing machine for razors or the like having concaved surfaces, the combination with a revoluble honing stone, a vertically and horizontally adjustable bracket, a 25 clamping cylinder eccentrically supported from said bracket and adapted to engage the razor between itself and the stone and a spring actuated means for pressing said clamping cylinder into clamping position. 30

In testimony whereof I affix my signature in presence of two witnesses.

JOHN KAYETAN.

Witnesses:

ELLIS V. LEVY,
MAX D. ORDMAN.
